ELECTRIC BOWLING GAME

Robert W. Cronk, Denville, N. J., assignor, by
mesne assignments, to Sutphen Products Cor-
poration, New York, N. Y., a corporation of New
York

Application May 25, 1946, Serial No. 672,309

9 Claims. (Cl. 273—41)

1

This invention relates generally to amusement apparatus and more particularly to a novel form of bowling game.

A prime object of the invention is to provide a novel target or objective for use in a ball rolling game, especially a simulated bowling game, in which the tenpins are dispensed with in their customary form and replaced by illuminated representations of pins and by movable discs disposed to be engaged by a ball rolled over the surface of the playboard so as to designate the positions of the several pins as the same are set up or spotted in the customary triangular array in an actual bowling game, the player exercising his skill in directing a bowling ball at the array of illuminated representations in an effort to effect a strike or to engage as many of the movable discs as possible, all in simulation of actual bowling practice, and wherein switch means are situated with respect to the movable discs so as to be actuated by said discs when the latter are engaged by the bowling ball.

A specific object is to provide in a bowling game or the like a plurality of movable discs forming part of the playing surface of the alley to designate the positions of the spotted or racked bowling pins, a playboard at the rear of the alley having representations of tenpins arranged to simulate the racked positions of bowling pins with lamps to illuminate said representations and switch means arranged with respect to the several movable discs so as to be actuated by said discs when the latter are engaged by a ball bowled, and said switch means when connected in an electric control circuit serving to effect an extinguishment of one or more of said lamps to indicate a hit, thus simulating the knocking over of one or more bowling pins.

A further object is to provide in a bowling game a novel and improved construction, combination and arrangement of primary switch control members, such as movable discs, each representing a bowling pin and arranged in simulation of the arrangement of bowling pins as set up in regulation bowling and disposed to be actuated by a ball rolled over the playing surface, secondary switch control members disposed to be actuated by the ball rolled over said playing surface, and switch means controlled by the rolling of a ball into contact with said control members to be connected in a circuit for electrical indicating mechanism to indicate the knocking down of one or more bowling pins.

Still another object is to provide a game of

2

this character that is simple in construction, inexpensive to manufacture, pleasing in appearance and effective in testing a player's bowling skill.

5 Other objects and advantages of the invention reside in the arrangement and combination of parts as hereinafter described and illustrated in the accompanying drawings in which—

Figure 1 is a side elevation of a bowling game 10 embodying my invention.

Figure 2 is a fragmentary top plan view of the apparatus of Figure 1.

Figure 3 is a front end view of the apparatus.

Figure 4 is a detail rear view of the lamp housing with the cover in open position.

Figure 5 is an enlarged sectional view taken on the plane of the line 5—5 of Figure 2.

Figure 6 is an enlarged sectional view taken on the plane of the line 6—6 of Figure 2.

20 Figure 7 is a diagram of the electrical circuits.

Figure 8 is a top plan view on an enlarged scale of the plate for supporting the disc members.

Figure 9 is a sectional view taken on the plane of the line 9—9 of Figure 8.

25 Figures 10 to 19, inclusive, are detail views showing the various disc members which form the switch actuating means.

Referring to the drawings, the apparatus includes a smooth playboard or alley 1 of any suitable length and width supported on legs 2 and bounded on its sides by walls 3. At the rear end of the alley is a transverse pit 4 into which the bowled ball rolls from the board for movement into a longitudinally directed ball return gutter 5 centrally supported beneath the alley by brackets 6 and inclined toward the front of the alley and by means of which the bowled ball is automatically returned for reuse at the front of the board or alley.

30 Instead of using bowling pins or tenpins as in the usual bowling game, the invention provides in lieu thereof a plurality of representations 7 of bowling pins as shown in Figure 3 adapted to be illuminated as hereinafter described. The representations are cut-out of a plate 8 of any suitable opaque material and are arranged in the familiar triangular array of bowling pins or tenpins. The plate 8 is supported in a vertical

35 plane between two panes 9 of glass or other suitable transparent material, suitably mounted in the front of a housing 10. The housing is supported on a transverse hollow box-like structure 11 at the rear of the pit 4. The box 11 has a movable front wall 12 and a fixed rear wall 13 with a compartment 14 therebetween.

40

45

50

55

Also preferably cut out of the plate 8 and extending across the top of the representations of the pins is the word "Strike" and similarly formed and arranged below the pins is the word "Spare."

In the rear of the plate 8, the housing is divided by vertical and horizontal partitions into compartments 15 at each side of the housing and extending to the height thereof and into transverse compartments 16 between the compartments 15 at the top and bottom of the housing. Between the compartments 15 and 16 are ten vertically disposed compartments 17 arranged to simulate the ordinary array of bowling pins, and between the individual compartments 17 in the upper row of said compartments are three smaller compartments 18.

The housing 10 is provided with a movable rear cover 19 hinged to the rear wall of the box 11 as indicated at 20. Mounted on the inner surface of this cover are ten vertically disposed lamps 21, a pair of horizontally disposed lamps 22 above the lamps 21 and a similar pair of lamps 23 below the lamps 21. The vertically disposed lamps are spaced and arranged to correspond with the spacing and arrangement of the compartments 17, and the horizontally disposed lamps 22 and 23 are arranged to correspond with the compartments 16 so that when the cover is closed as in Figure 5, the individual lamps 21 are housed in separate compartments 17 and are in alignment with the representations 7, the horizontally disposed lamps 22 are housed in the upper compartment 16 in alignment with the word "Strike" and the horizontally disposed lamps 23 are housed in the lower compartment 16 in alignment with the word "Spare." The lamps are operatively connected to a source of electro-motive force such as the house supply but such connections are only shown diagrammatically in Figure 7.

Also mounted on the inner surface of the cover 19 along its side edges are a number of relay devices 24, which are in circuit with the lamps. These relays are housed in the side compartments 15 when the cover is closed.

The alley adjacent its rear end where the tenpins are ordinarily positioned is formed with a cutout portion and secured in this cutout portion by means of bolts 25 is a plate 26. This plate has a number of openings 27 and countersunk or recessed portions 28 in the top thereof. The openings with their recesses are arranged in the familiar triangular array of bowling pins or tempins. Supported by plate 26 and spaced downwardly therefrom by means of bolts 29 is another plate 30 having openings 31 corresponding in number to and in alignment with the openings 27 in plate 26.

Depending below and secured to the lower plate 30 by means of brackets 32 are a number of microswitches 33, said switches being disposed under and in alignment with the openings 31 in plate 30.

Mounted in the openings and recesses of the plate 26 are a number of disc members with their upper surfaces substantially flush with the upper surface of the alley, which members are adapted to be depressed when the ball rolls over them so as to actuate corresponding ones of the switches 33. Each member has a disc portion 34 and a depending hub portion 35 with a central recess 36 in its lower surface. Carried by each hub portion is a stem or post 37 extending downwardly loosely through a screw-threaded bush-

ing 38 mounted in the threaded opening 31 of the lower plate 30. A helical spring 39 encircles each stem and is interposed between the hub portion and the bushing to maintain the disc member in a position with its upper surface flush with the upper surface of the alley. Carried by the bottom end of each stem is a screw member 40 the lower end of which is in engagement with the movable contact of the switch 33 for actuating said switch.

The threaded bushing is adapted to adjust the tension of the spring and thereby the height of the disc member. The screw member 40 is adapted to adjust the pressure on the switch 15 and may be provided with a nut 41 to hold the parts in adjusted position.

As will be apparent from Figures 10 to 19, inclusive, the disc portions of the various disc members are of various shapes and sizes and the hub portions are of various sizes to fit in the various sized recesses and openings in the plate 26.

The disc member 42 shown in Figures 10 and 11 has an arcuate-shaped slot 43 formed in the periphery of its disc portion and is arranged to actuate the one of the switches 33 that is designated 42a in Figure 7. Such a disc member is mounted in each of the end openings 44 in the upper three rows of openings shown in Figure 8 30 with the slotted portion of the disc portion facing inwardly.

The disc member 45 shown in Figures 14 and 15 constituting a primary switch control member has oppositely disposed arcuate-shaped peripheral slots 46 and 47 in its disc portion and such a disc member is mounted in each of the intermediate openings 48 in the upper two rows of openings in Figure 8 and is arranged to actuate the one of the switches 33 that is designated 45a in Figure 7.

A disc member 49 such as shown in Figures 12 and 13 constituting a secondary switch control member is mounted in each of the openings 50 between the openings 44 and 48, the disc portion 45 thereof being positioned in the space between the arcuate-shaped portions of adjacent disc members and said disc member being arranged to actuate one of the switches 33 that are designated 49a in Figure 7.

A head disc member 51 representing the head, apex or king pin as shown in Figures 16 and 17 and also constituting a primary switch control member has its disc portion formed with arcuate-shaped peripheral slots 52 disposed opposite to each other but above the center of the disc portion and smaller than the slots in the disc portions of disc members 42 and 45. This disc member is mounted in the large central opening 53 in the lowermost row of openings shown in Figure 8 with its slotted portions uppermost, said member being arranged to actuate the one of the switches 33 that is designated 51a.

A strike disc member 54 also constituting a secondary switch control member smaller than but of similar construction to disc member 49 and representing the point at which a ball must roll to produce a strike, is mounted in each of the smaller openings 55 in the lowermost row 70 of openings as shown in Figures 2, 6 and 8 with its disc portion overlapping the hub portion of the disc member 51 but spaced therefrom whereby either member 54 may be depressed to actuate its corresponding switch that is designated 54a 75 or 54b (see Figure 7) without moving the mem-

ber 54. This disc member is shown in Figures 18 and 19.

The disc members 49 have their disc portions overlapping the hub portions of the disc members 42 and 45 in spaced relation thereto so that the members 49 may be depressed to actuate their respective switches without moving the members 42 and 45. If the ball rolling over the discs does not depress both the disc 49 and the discs 42 and 45 overlapped thereby, then the double pole switch 49a will be actuated to extinguish both the lamps corresponding to said discs 42 and 45. If the rolling ball depresses only the disc 42 or the disc 45, only the corresponding lamp will be extinguished.

Referring to the diagram of Figure 7, the lamps 21 are shown to the right of the figure and the relay devices 24 are shown underneath the lamps. The lamps and relay devices are arranged in the usual manner of spacing tempins in a bowling game so that each lamp and its corresponding relay represent one of the pins. The switches 33 are shown to the left of the figure and are similarly arranged. It will be understood by those skilled in the art that various arrangements and types of switches may be employed and connected in circuit in different ways to correspond to various possible plays or various ways in which the pins may be knocked down by a ball in a regular game, and in the drawings and this description, it has been attempted to illustrate only a few of the possibilities. The source of power is indicated at 56. A line 57 connects the lamps and relay devices with this source of power.

The lamps 21 are arranged in parallel, each having its own connecting line 58 and lead 59.

The bank of relay devices 24 are also connected in parallel, one side of each device being connected by a line 60 to the line 57 at point 61.

From the opposite terminal of the source 56 there is an electric lead 62 which by means of connecting points 63 leads to one side of each of the switch members 33, these connections being indicated at 64. The three switches in the lowermost row of switches are single pole, single throw microswitches, while in the other rows every other switch is a double pole, single throw switch. The central switch in the lowermost row has its other side connected by a line 65 to the other side of the lowermost or apex relay device of the bank of relay devices. The other sides of the switches in the other rows are connected to the other sides of the relay devices in the corresponding rows of the bank of relay devices by similar lines 65. The armature of each of the relay devices is adapted to be connected to a lamp 21 by means of the lead 59. Thus for instance, considering the relay device 24 at the apex of the triangular arrangement of relay devices, this has the communicating lead 59 to the apex lamp 21 of the bank of lamps. Thus in sequence the armatures of the relay devices in the second row are connected to the lamps in the corresponding second row of the bank of lamps, and the relay devices in the third and fourth rows are connected to the lamps in the corresponding rows of the bank of lamps. It is not necessary to enumerate each of the separate electric leads. In Figure 7, it is presumed that the apex relay device for the apex lamp is at the bottom of the set.

The present invention also provides mechanism for preventing the possibility of a so-called "cross strike" and also mechanism for auto-

matically setting up the parts for a possible "spare" in case a "strike" is not scored with the first ball. This latter mechanism includes a microswitch 66 in the compartment 14 in the box 11 in back of the movable wall 12. This wall is urged forward by a helical spring 67 interposed between the front and rear walls and supported on lugs 68 extending inwardly from said walls. A pad 69 is preferably mounted on the outer face of the movable wall 12 to cushion the shock of the ball. The movable wall carries a stem 70 which has a screw member 71 on its inner end adapted to engage the movable contact of the switch 66 and actuate the latter.

Referring to Figure 7, switch 66 is connected to the lead 62 by means of a line 72 and is connected on its other side by a line 73 to one side of a relay device 74, the other side of the device being connected by line 75 to the lead 57.

A single pole double throw relay device 76 has one side connected by line 77 to lead 57 and has its other side connected by line 78 to line 65 leading to the apex relay device. The armature of this relay 76 is connected to the other sides of the end switches 33 in the lowermost row of switches of the bank of switches, by a line 79. A single pole double throw relay device 80 has one side connected to the line 77 by a lead 81 and its other side connected by a line 82 to the armature of relay device 76. One side of lamp 22 for illuminating the word "Strike" is connected by line 83 to the armature of relay device 80, the other side of said lamp being connected to the lead 57 by the line 84. Another single pole double throw relay device 85 has one side connected by line 86 to the armature of relay device 76 and has its other side connected by line 87 to the armature of relay device 74. One side of lamp 23 for illuminating the word "spare" is connected by line 88 to the line 84 leading to lead 57 and its other side is connected to the armature of relay device 85, by line 89. The armatures of all of the relay devices 24 are connected by line 90 to the armature of relay device 80.

Figure 7 illustrates the condition of the circuit control means when the game is ready for play. All of the lamps 21 are illuminated and the lamps 22 and 23 for illuminating the words "strike" and "spare," respectively, are extinguished. The arrangement is such that a ball bowled at the illuminated "pins" will engage certain disc members embedded in the alley and actuate certain of the switches and associated relay devices so that a lamp 21 corresponding to the switch struck will be extinguished, or if a direct hit is made on one of the so-called "strike" discs 54, a "strike" will be scored, all of the lamps 21 will be extinguished and the lamp 22 will be illuminated to show the word "strike," or if a "spare" is scored the lamp 23 will be illuminated to show the word "spare."

The player rolls the ball skillfully over the alley aiming at the illuminated "pins" in an effort to hit one of the so-called strike disc members 54 to which the king pin switch 54a or 54b is connected. This play if successful, that is, if a direct hit is scored on one of the "strike" discs 54, constitutes a "strike" corresponding in regulation bowling to the knocking over of all ten pins and effecting in the present instance the extinguishing of all of the lamps 21 and the illumination of the lamp 22 for illuminating the word "strike." Such a direct hit actuates either

the switch 54a or the switch 54b, as the case may be, thereby energizing the coil of the relay 80 so that the common lead wire 88 from all of the armatures of relays 24 to all of the lights 21 is opened and all of the lights are extinguished. At the same time, the armature of the relay 80 is connected to line 83 whereby lamp 22 is illuminated to show the word "strike."

However, should the ball roll over the head or apex disc member before entering the "strike" area, a strike will not be scored. In such event, when the ball strikes the wall 12 at the rear of the pit 4 it will actuate switch member 66, closing the same and thereby energizing relay device 14 which resets the parts for a possible "spare;" also, the parts will be set for a "spare" by closing of switch 51a and consequent energization of relay 76. The player rolling his second ball may roll to hit the apex disc member or "strike" disc member which is now set up for a "spare" or he may aim to "hit" the remaining illuminated "pins" whichever in his judgment presents the best target. The present invention differs from the regulation bowling technique in this particular because the present invention does not have the advantage of one pin downing surrounding pins. A "spare" will be scored when the first ball closes switch 51a and the second ball closes either the switches 54a and 54b, the relay device 85 thus being energized and drawing its armature into contact with line 89 to illuminate the lamp 23 to show the word "spare." Obviously, there are certain situations in regular bowling that cannot be duplicated with my game as described, for example, the scoring of a "spare" by rolling a ball over one of the end discs representing one pin left standing. Furthermore, certain conditions arise that are not found in a regular bowling game, for example, should a second ball close switch 54a or 54b after failure of the first ball to close any of the switches 51a, 54a or 54b, a "strike" would be scored; and the regular bowling rules would be modified accordingly.

The various mechanisms are accessible for easy adjustment, servicing and replacement. A gauge may be used to keep the disc and switch members in constant adjustment if desired.

Changes in details of construction might be resorted to without departing from the principle or scope of the invention and I desire to be limited only by the state of the prior art and the appended claims.

What I claim is:

1. In an electrical bowling game, an alley having a playing surface, an electrical circuit control means comprising primary switch control members each representing a bowling pin and arranged in simulation of the arrangement of bowling pins as set up in regulation bowling and disposed to be actuated by a ball rolled over said playing surface, two secondary switch control members disposed to be actuated by a ball rolled over said playing surface and arranged at opposite sides of and adjacent the primary switch control member that represents the head pin at locations corresponding to that at which a bowling ball must hit the pins to cause a "strike," switch means controlled by actuation of said control members by a ball rolling over said playing surface into contact with said control members, and pin and strike scoring circuits controlled by said switch means.

2. In an electrical bowling game as defined in claim 1, additional secondary switch control

members to be engaged by a ball rolled over said playing surface and located between said primary switch control members that are arranged in spaced relation transversely of said playing surface, switch means controlled by actuation of said additional control members by a ball rolling over said playing surface into engagement with said additional control members, and pin scoring circuits controlled by said switch means.

3. An electrical bowling game, comprising an alley having a playing surface, an electrical circuit control means including a main disc member representing each bowling pin forming a portion of said playing surface and arranged with respect to the other disc members in simulation of the arrangement of bowling pins as set up in regulation bowling and disposed to be engaged by a ball rolled over said playing surface, a similar but smaller disc member also forming a portion of said playing surface to be engaged by a ball rolled over said playing surface and disposed at each of opposite sides of and contiguous to the main disc member that represents the head pin at a zone corresponding to that over which a bowling ball must roll to hit regular bowling pins to cause a "strike," a switch for each disc member actuated by the rolling of a ball over said playing surface into contact with said disc member, and pin and strike scoring circuits controlled by said switches.

4. An electrical bowling game as defined in claim 3, wherein said main disc member that represents the head pin has notches and said smaller disc members have portions nested in said notches.

5. An electrical bowling game as defined in claim 3, with the addition of small disc members located between said main disc members that are arranged in spaced relation transversely of said playing surface and disposed to be engaged by a ball rolled over said playing surface, a switch means for each said small disc member actuated by the rolling of a ball over said playing surface into contact with said small disc member, and pin scoring circuits controlled by said switch means.

6. An electrical bowling game as defined in claim 5, wherein each main disc member has a notch in its edge and said smaller disc members have portions nested in the notch in the edge of each of the adjacent main disc members.

7. An electrical bowling game as defined in claim 5, wherein each main disc member has a notch in its edge and said smaller disc members have portions nested in the notch in the edge of each of the adjacent main disc members and overlapping in vertically spaced relation thereto portions of the adjacent main disc members so that said smaller disc members may be actuated without moving their adjacent main disc members.

8. The electrical bowling game as defined in claim 3, wherein said alley includes a plate whose upper surface is flush with the playing surface of the alley, and each disc member has a disc part and a hub part, said plate having holes therethrough in which the hub parts of said disc members are slidably, said plate also having recesses in its upper surface each in register with one of said holes and in which the disc part of one of said disc members is located.

9. The electrical bowling game as defined in claim 3, with the addition of a spring normally actuating each disc member to locate the top

of the corresponding disc member substantially flush with the surface of said alley and yieldable to permit said disc member to be depressed upon the rolling of a ball thereover.

ROBERT W. CRONK.
